UNITED STATES PATENT OFFICE.

WALDEMAR PETERSEN, OF DARMSTADT, GERMANY.

HIGH-VOLTAGE PROTECTION.

1,153,821.

Specification of Letters Patent. Patented Sept. 14, 1915.

Application filed September 21, 1914. Serial No. 862,867.

To all whom it may concern:

Be it known that I, WALDEMAR PETERSEN, subject of the German Emperor, and resident at Darmstadt, Grand Duchy of Hesse, German Empire, have invented certain new and useful High-Voltage Protection, of which the following is a specification.

Figure 1 shows the arrangement consisting of the combination of a choking coil *a* and a condenser *c* commonly employed for protecting transformers, for example, from excess voltages. This arrangement can particularly if the mains have a very low resist-

15 ance to waves $\sqrt{\frac{L}{C}}$ become the seat of excess

voltages which endanger the protected apparatus. The combination of choking coil and condenser as is known forms a system capable of setting up oscillations which in the limited case upon the approach of a sufficiently long traveling wave to the protected apparatus can produce an excess voltage of 25 three times the magnitude. The excess voltage can be still higher if there is a short circuit in the conductors to the ends of which the protecting device is connected at such a distance that the natural period of the short circuited length of conductor is identical 30 with the natural period of the protecting device. This source of danger particularly arising in networks of cables can be avoided by connecting a resistance *b* to destroy the 35 effect across the ends of the choking coil *a* (Fig. 2) in known manner; but according to the invention the magnitude of this resistance must be designed in relation to the self-induction of the choking coil *a* and the capacity of the condenser *c*, so that the natural 40 oscillation of the protecting device is strongly or altogether suppressed. Apart from any damping effect in the oscillatory circuit *a c* the following is the differential equation of 45 this oscillatory circuit:

$$\frac{d^2i}{dt^2} + \frac{1}{R.C} \frac{di}{dt} + \frac{1}{L.C} i = 0$$

50 where *i* is the instantaneous value of the current flowing through the choking coil *a*, *R* is the resistance of *b*, *L* is induction of *a* and *C* the capacity of the condenser *c*. The system *a c* is deprived of the capacity to set up oscil-

lations as the solution of this differential equation shows if the magnitude *R* of the resistance *b* has the value.

$$R = \frac{1}{2} \frac{L}{C}$$

For preventing harmful rises in voltage it 60 is not necessary to choose this critical value, any other higher resistance can be taken which damps the natural oscillation to such an extent that in the second half-period of the natural oscillation a certain allowable 65 limit of voltage is not exceeded and thus the known resonance phenomena cannot arise.

Bridging across inductances is as already 70 stated in itself a known procedure many times published, yet in all these cases the object forming the basis of the present invention is not pursued.

The insertion of a resistance in parallel 75 has had for its purpose, for example, the possibility of annulling an approaching wave and the magnitude of the resistance must be chosen in a definite ratio to the resistance to waves of the mains, while in the arrangement forming the subject-matter of the invention 80 the parallel resistance in the first place is determined from the properties of the choking coil of the condenser.

The most favorable bridging over resistance under some circumstances is so low that 85 a considerable portion of an approaching traveling wave passes through the resistance and damages the protected parts of the apparatus before the condenser *c* comes into operation. The effectiveness is therefore still further increased if the arrangement illustrated in Fig. 3 is shown. In this the resistance *b* is in fact connected in parallel with a part of the protecting choking coil *a*. The portion *d* of the choking coil lying in front 95 of the resistance prevents traveling waves from passing through, at least for a short time. Also, in this arrangement it is possible to deprive the system of any possibility of oscillating or to strongly damp the natural oscillations.

Having now particularly described and ascertained the nature of my said invention and in what manner the same is to be performed, I declare that what I claim is:

1. The combination with a line wire having 105 a choke coil interposed therein, of a

branch wire leading from one side of the choke coil, a condenser having one side connected to the branch wire, a ground connection to the other side of the condenser, a resistance branching off from the branch wire and having parallel connection to the choke coil.

2. The combination with a line wire having a choke coil interposed therein, of a branch wire leading from one side of the choke coil, a condenser having one side connected to the branch wire, a ground connection to the other side of the condenser, a re-

sistance branching off from the branch wire and having parallel connection to the choke coil intermediate the ends of the choke coil whereby a portion of the choke coil is interposed between the resistance connection and the one end of the line wire. 15

In testimony, whereof I have signed my name to this specification in the presence of two subscribing witnesses.

WALDEMAR PETERSEN.
